PULL FOR SLIDING DOORS

Morton Tucker, 1395 E. 11th Ave., Hialeah, Fla.

Filed June 6, 1963, Ser. No. 75,252

Term of patent 3½ years

(Cl. D10—8)

FIG. 1

FIG. 2

FIG. 3

FIG. 4

I claim:

The ornamental design for a pull for sliding doors, as shown.
